UNITED STATES PATENT OFFICE

JOHN H. LOOMIS, OF LUDINGTON, MICHIGAN, ASSIGNOR, BY MESNE ASSIGNMENTS, TO
ST. JOSEPH IRON WORKS, OF ST. JOSEPH, MICHIGAN, A CORPORATION OF MICHIGAN

APPARATUS FOR ASSEMBLING BASKET ELEMENTS

Application filed April 14, 1926. Serial No. 101,972.

My present invention has to do with the manufacture of baskets, and it contemplates the provision of a process and apparatus through the medium of which the elements that enter into a basket may be expeditiously and easily assembled and may be held in proper relative position to form a perfect basket before placing of the assembled and correctly positioned elements upon a stitching machine.

Other objects and practical advantages of the invention will be fully understood from the following description and claims when the same are read in connection with the drawings, accompanying and forming part of this specification, in which:

Figure 1 is a side elevation illustrative of basket elements assembled and retained in proper relative position through the medium of my invention.

Figure 2 is a top plan view of the same.

Figure 3 is a diametrical section illustrating the same assembly as Figures 1 and 2 and taken on the line 3—3 of Figure 2.

Figure 4 comprises disconnected perspectives of the interior band and the exterior hoop included in the apparatus forming part of my invention.

Figure 5 is a perspective of the base mandrel also included in said apparatus.

Figure 6 is a perspective view of the basket as it comes from the stapling machine.

Similar numerals of reference designate corresponding parts in all of the views of the drawings.

For the sake of convenience and clearness, the process that forms part of my present invention will be described and made clear incident to the disclosure of the apparatus and the mode in which the apparatus is employed in the practice of my invention.

Among other elements the apparatus comprises an exterior hoop 1 which may be of any material compatible with its purpose. The apparatus also includes an interior band 2 which is of taper form and wider than the hoop in about the proportion illustrated. The said band 2 like the hoop 1 may be of any appropriate material possessed of the

requisite stiffness for the purpose to which they are put.

In addition to the hoop 1 and the band 2, my novel apparatus comprises a mandrel 3, shown in detail in Fig. 5. The said mandrel is made of a body 4 which for facility in handling is hollow and is made up of heads 5 and 6 spaced apart with a tapered wall 7 permanently joining the heads 5 and 6. Ribs 8 are secured as at 15 on the said wall 7 and extend throughout the height thereof, the space between each pair of ribs being sufficient to accommodate a basket stave 14 therebetween. An annulus 9 surrounding and spaced by the ribs 8 from the wall 7 is secured as at 16 to the ribs 8 and to the wall 7. Upright spaced ribs 10 are secured at 17 on the outer side of the said annulus 9 opposite the spaces between the ribs 8, and the ribs 10 are spaced apart to admit the lower ends of the outer basket staves therebetween. A taper band 11 is removably arranged about the ribs 10 and snugly engages the same so as to be held against casual displacement by frictional contact.

The basket comprises a bottom 12 with annular flange as shown particularly in Fig. 3, and the side wall consists of a series of laterally spaced inner staves 14 and a series of laterally spaced outer staves 13, the latter of which are arranged over the spaces between and overlap the edges of the inner staves as shown particularly in Fig. 2, and in the finished basket these staves are stapled or otherwise fastened to upper, lower and intermediate outside hoops 18, 19 and 20 respectively and to the upper inside hoop 21 and also to the annular flange of the bottom 12.

More specifically speaking the use of my novel apparatus is as follows, namely, the tapered band 2 is superposed on the mandrel 3 as shown in Fig. 3 and the bottom 12 is set upon the upper edge of the band 2 as also shown in said figure, after which the inner series of staves 14 are set in place around the apparatus with their lower portions between the ribs 8 and between the band 9, and the tapered wall 7. The outer series of staves 13 are then placed in position with

their lower ends between the ribs 10 and between the bands 9 and 11, after which the hoop 1 is slipped downwardly over the staves 13 and 14 so as to clamp the upper portions of the staves against the band 2 and against the marginal flange of the bottom 12. Manifestly with this done the staves, the bottom 12, the hoop 1, and the interior band 2 which latter is loose on the mandrel 3 may be readily separated from the mandrel 3, at which time the lower ends of the staves 13 and 14 are withdrawn from between the ribs 8 and 10, and the removed structure is then applied to a stitching machine which secures the staves to the flange of the bottom 12 and secures the hoops 18, 19, 20 and 21 to the staves. After the stapling operation is completed the hoop 1 is removed and the band 2 withdrawn from the interior of the basket, the taper of the basket permitting such removal to be readily accomplished.

Notwithstanding the practical advantages of my invention as pointed out, it will be noted that the elements of the apparatus are simple and inexpensive, and are susceptible of being readily manipulated with but little effort, and that by the practice of the process the elements that enter into the construction of the basket may be expeditiously and easily assembled and conveniently retained in proper relative position for presentation to means for permanently connecting the elements together, which means may be of any type, consonant with the purpose of my invention.

I have specifically described the peculiar construction and relative arrangement of the parts comprised in the present and preferred embodiment of my invention in order to impart an exact understanding of the said embodiment. I do not desire, however, to be understood as confining myself to the specific construction and relative arrangement disclosed, my invention being defined by my appended claims within the scope of which structural changes and changes in arrangement may be made without departure from my invention.

Having described my invention, what I claim and desire to secure by Letters Patent, is:—

1. Apparatus for use in the assembling of elements that enter into a basket or the like, comprising a tapered mandrel, means thereon for maintaining staves in spaced relation, means for confining said staves about the mandrel, a tapered band removably superposed on the mandrel and adapted to rest removably in a group of staves, and a hoop removably surrounding the staves and adapted to retain the same in engagement with a bottom positioned upon the tapered band within the upper ends of the staves.

2. In an apparatus for the purpose described, a mandrel comprising a hollow

tapered body having a side wall, spaced ribs extending throughout the height of said side wall at the outer side thereof, a band or annulus surrounding the lower portions of said ribs and fixed with respect thereto and having on its outer side spaced ribs opposite the spaces between the first mentioned ribs, in combination with a removable band surrounding the last-named ribs and adapted to retain staves in the spaces between said ribs. 75

3. A mandrel for use in facilitating the assembling of basket elements, comprising a body tapered as to height and characterized by exterior spaced ribs extending throughout the height of the body, and a band surrounding said ribs and having on its outer side spaced upright ribs opposite the spaces between the first mentioned ribs. 80

4. A mandrel characterized by a tapered body, a band spaced from the lower portion of the body with means at the inner side of the band dividing the space between said band and the taper body into a plurality of sections, and exterior spaced upright ribs on the said band and circumferentially 90 spaced from the aforesaid means.

5. In an apparatus of the class described, the combination of a form including a main section and a removable section, and means cooperating with said removable section to hold a plurality of panels around the form and permit removal of the panels and said removable section from the remainder of the form, and an inner and outer series of guides on the main section for locating an inner 100 and an outer series of panels around the form, said guides of one series being circumferentially spaced from the guides of the other series.

6. In an apparatus of the class described, the combination of a base and a removable section mounted thereon and constituting a form, a ring for clamping a plurality of panels against the removable section and around the form so as to leave the portions of the panels around the base free to be disengaged therefrom, and an inner and an outer series of guides on the base for positioning an inner and an outer series of panels around the form, said guides of one series 115 being circumferentially spaced from the guides of the other series. 110

In testimony whereof I affix my signature.
JOHN H. LOOMIS.
